(57) **CLAIM**

We claim the ornamental design for a faucet, as shown and described.

DESCRIPTION

FIG. 1 is a top, front, right perspective view of an embodiment of the claimed design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The ornamental design which is claimed is shown in solid lines in the drawings. The broken lines in the drawings are for illustrative purposes only and form no part of the claimed design. Broken lines formed by equal length dashes show unclaimed subject matter. Broken lines formed by unequal length dashes (i.e., dash-dot) define bounds of the claimed design. Broken away symbols having a jagged element depict unspecified length. The appearance of any portion of the article between the broken away symbols forms no part of the claimed design.
